(57) **CLAIM**

The ornamental design for a treatment apparatus for endoscope, as shown and described.

DESCRIPTION

FIG. 1 is a perspective view of a treatment apparatus for endoscope;

FIG. 2 is an enlarged fragmentary front view thereof;

FIG. 3 is an enlarged fragmentary rear view thereof;

FIG. 4 is an enlarged fragmentary top plan view thereof;

FIG. 5 is an enlarged fragmentary bottom plan view thereof;

FIG. 6 is an enlarged fragmentary left side view thereof; and,

FIG. 7 is an enlarged fragmentary right side view thereof.

The portion of the article shown in broken lines is for illustrative purpose only and forms no part of the claimed design.
